DRIVE SYSTEM FOR ROLLER COASTERS

Charles L. Cooper, Los Angeles, Calif.

Application January 8, 1951, Serial No. 204,943

2 Claims. (Cl. 104—63)

1

This invention relates to vehicular systems of the type exemplified by the familiar roller coaster, in which unpowered cars running on an endless track are first carried up an ascending section of the track by a power-driven chain and then continue their travel back to the starting point by gravity. The invention has to do particularly with the method and mechanism employed to get the cars into motion out of the starting station.

An object of the invention is to rapidly and positively accelerate the cars from a standing start at the starting station.

Another object is to reduce power consumption when the cars are not being drawn.

Other more specific objects and features of the invention will appear from the description to follow.

The conventional roller coaster system has a track that slopes downwardly from the starting station to the base of an ascending, inclined section, and the latter is provided with a constantly running chain that engages the cars as they reach the base of the inclined section and pull them up, the cars disengaging from the chain as they pass over the top of the incline and start their downward travel under the force of gravity. As each car completes its run and enters the starting station, it is stopped by a brake, and the track being downwardly inclined at the starting station the car can be started by gravity on another trip by simply releasing the brake.

This well known prior system has the disadvantages that:

(1) Acceleration out of the starting station is slow;

(2) It is practically impossible to so control the gravity acceleration of the car between the starting station and the point where the constantly moving chain picks it up, that the speed of the car approximates that of the chain, so that the chain picks up the car with a jerk that is unpleasant to the passengers and is hard on the equipment;

(3) The chain is driven constantly at fixed speed with resultant power waste and constant noise and wear.

In accordance with the present invention, I eliminate the aforesigned disadvantages by causing the chain to engage the car in the starting station, stopping the chain except when it is moving a car, and accelerating the chain and car together from a standing start to move the car rapidly out of the station and up the incline. I further provide a power system for the chain consisting of a prime mover, such as an internal

2

combustion engine, coupled to the chain by a fluid drive clutch. When the cars are not being moved, the engine is idled, and the clutch slips, permitting the chain to be held stationary by engagement with a car in the starting station. To set the car in motion, its brakes are released, and the engine is accelerated, causing automatic increase in the torque transmitted through the fluid clutch. The engine then rapidly picks up the load with a smooth acceleration.

A full understanding of the invention may be had from the following description which refers to the drawing.

In the drawing:

15 Fig. 1 is a plan view of a very simple roller coaster system incorporating the invention;

Fig. 2 is an enlarged elevational view taken in the plane II—II of Fig. 1;

Fig. 3 is a detailed horizontal section taken in the plane III—III of Fig. 2;

Fig. 4 is a detailed cross-section in the plane IV—IV of Fig. 2;

Fig. 5 is a detailed longitudinal vertical section in the plane V—V of Fig. 1;

25 Fig. 6 is a cross-section in the plane VI—VI of Fig. 5; and

Fig. 7 is a detailed vertical longitudinal section through the rear portion of a car and the track showing the driving engagement between the chain and the car.

Referring to Fig. 1 there is shown an endless track 10 having a station section 10b and an ascending inclined section 10a extending therefrom. The rest of the track from the top of the inclined section 10a back to the station section 10b has an average downward inclination, to cause the cars 11 to move by gravity back to the starting station section, which is preferably substantially level. The cars may be stopped at the starting section by the usual braking mechanism, one form of which is illustrated in Figs. 5 and 6 to be described later. The cars are moved out of the starting station by a power-driven chain 12, which is trained over sprocket wheels 13, 14, 15, and 16, and extends under at least a portion of the station section of the track and all of the ascending inclined section 10b. One of the sprockets, in this instance the sprocket 14, is power-driven to move the chain, and the remaining sprockets are idlers. The main portion of the upper reach of the chain 12 is in the plane of the track and midway between the track rails 10c, 10c. As shown in Fig. 4, the chain 12 may slide along a center rail 18 which rests in a channel member 19 the upwardly extending

flanges 19a of which serve as lateral guides for the chain.

Each car 11 may be provided with a downwardly depending hook 20 (Fig. 7) extending into the path of the chain 12 for engaging the latter and causing the chain to propel the car when the chain tends to move faster than the car. The hook is hingedly supported from the car at its upper end by a pin 21 so that it can swing out of engagement with the chain when the forward movement of the car exceeds that of the chain.

The drive sprocket 14 is shown powered by an internal combustion engine 22 (Figs. 1 and 3), which has built integral with it a fluid drive clutch 23, through which the engine drives a shaft 24. The shaft 24 is coupled through a universal joint 25 and a gear box 26 with a shaft 27 to which is keyed the drive sprocket 14.

As is well known, a fluid drive clutch has the characteristic of transmitting very little torque at low speed but substantially full torque at normal running speed. Therefore, when the engine 22 is idling very little torque is applied to the drive sprocket 14, and the latter can be held stationary by its own frictional resistance to motion or by the resistance of a car held in the starting station by the usual brake. However, when the engine is accelerated by opening the throttle 30, substantial torque is applied to the shaft 24, and if the latter is free to turn, the torque increases as the shaft speed increases, resulting in the shaft speed increasing substantially to the engine speed.

As shown schematically in Figs. 5 and 6, a suitable brake for stopping and holding the car in the starting station may comprise a pair of horizontal, elongated brake shoes 31 extending between the rails 10c of the track and in vertical alignment with brake elements 32 on the undersides of the cars. The brake shoes 31 are supported on cams 33 which are mounted on cross shafts 34 journaled at their ends in frame members 35. Each cross shaft 34 has an arm 34a thereon and the outer ends of the arms 34a are pivotally connected to a link 36, which in turn is pivotally connected to the lower end of a brake lever 37, located adjacent the throttle lever 30. It will be observed that by swinging the upper end of the lever 37 clockwise, with reference to Fig. 5, the brake shoes 31 are raised to engage the undersides of the brake elements 32 on the cars and stop the latter.

In operation, as a car or train of cars 11 finishes its run and enters the starting station it is brought to a halt by manipulation of the brake lever 37 to apply the brakes, in accordance with prior practice. Prior to this time, the engine 22 will have been slowed to idling speed by closure of the throttle 30, so that if the friction of the chain 12 itself is not enough to stop it, it is stopped by engagement with the hook 20 on one or more of the stopped cars.

The cars are started on a new run by simply releasing the brake lever 37 and opening the throttle 30 to accelerate the engine 22. This applies traction to the chain through the fluid drive 23, and the chain and cars accelerate together, carrying the cars out of the starting station and up the ascending inclined section 10b of the track. The engine 22 is preferably so proportioned to the load as to accelerate the chain and

cars substantially to full running speed before the cars reach the incline, so that the cars get away to a smooth but fast start immediately after they start to move. After the cars have 5 passed the top of the ascending section of the track and have left the chain, they are propelled by gravity, and the throttle is closed to slow the engine to idling speed.

Although for the purpose of explaining the invention, a particular embodiment thereof has been shown and described, obvious modifications will occur to a person skilled in the art, and I do not desire to be limited to the exact details shown and described.

I claim:

1. In a vehicular system of the type described: a track having an approximately level loading station section merging into an ascending inclined section; a drive chain and means supporting a section thereof parallel to and in close proximity to said station and inclined sections of said track; a car on said track and means for coupling said car to said chain during movement of said car over said station and inclined sections of the track for propulsion of the car by said chain; a variable speed prime mover; brake means for selectively holding said car stationary on said station section of said track; and means for coupling said prime mover in driving relation to said chain comprising a fluid drive clutch the power transmitting characteristic of which varies with the speed of said prime mover.

2. In an amusement ride system comprising an endless track with cars thereon, said track having a loading section on which the cars are stopped, an ascending section leading from the loading section, and a coasting section extending from the top of the ascending section back to the loading section over which the cars are propelled by gravity; braking means for stopping and holding cars on said loading section; a drive chain and means supporting a portion thereof parallel to and in close proximity to said station and ascending sections of said track means for positively coupling each car to said chain against rearward movement relative to the chain while it is juxtaposed to said portion of said chain; a driving motor; and transmission means including a slippable clutch coupling said motor to said chain, whereby stoppage of a car in said loading section by said brake stops said chain by slipping said clutch, and releasing the brake and engaging the clutch accelerates said chain, and accelerates the car engaged thereby out of said loading section and up said ascending section of track.

CHARLES L. COOPER.
